UNITED STATES PATENT OFFICE.

JAMES M. McCLELLON, OF EVERETT, MASSACHUSETTS.

FIRE-BOX FOR BOILERS.

1,111,266.

Specification of Letters Patent. Patented Sept. 22, 1914.

Application filed October 1, 1909. Serial No. 520,556.

To all whom it may concern:

Be it known that I, JAMES M. McCLELLON, a citizen of the United States, and a resident of Everett, in the county of Middlesex and 5 Commonwealth of Massachusetts, have invented an Improvement in Fire-Boxes for Boilers, of which the following description, in connection with the accompanying drawings, is a specification, like letters on the drawings representing like parts.

My invention relates to fire-boxes for boilers and more particularly to fire-boxes of the locomotive type.

The character of my invention may be best understood by reference to the following description of an illustrative embodiment thereof shown in the accompanying drawings wherein:

Figure 1 is a front elevation of a locomotive fire-box embodying my invention; Fig. 2 is a vertical section taken on line 2—2 of Fig. 1; Fig. 3 is a transverse vertical section through the fire-box; Fig. 4 is a vertical section taken on line 4—4 of Fig. 3; Fig. 5 is a horizontal section taken on line 5—5 of Fig. 1; Fig. 6 is a vertical section taken on line 6—6 of Fig. 3; Fig. 7 is a section taken on line 7—7 of Fig. 6; Fig. 8 is a section taken on line 8—8 of Fig. 3; and Fig. 9 is a section taken on line 9—9 of Fig. 1, looking upward.

Referring to the drawing, the fire-box herein shown as embodying my invention is illustrated in connection with a boiler of the 35 locomotive type, a portion of a locomotive cab 1 (Fig. 1) and the barrel 3 (Figs. 3, 4 and 9) of the boiler being shown.

The fire-box comprises side walls 5 (Fig. 3) each comprising in turn a plurality of 40 open sided, unitary sections 7, arranged transversely to the length of the fire-box. To provide a wall which will be inextensible and stable as a whole and at the same time be of sufficient local or unit flexibility 45 and expansibility to expand and contract in response to variations in temperature without buckling, stressing or weakening, each of the wall sections is made to present a flexion side or portion 8 conveniently curved, 50 bulged or convexed in cross-sectional shape at the inner or fire-side of the wall. The adjoining or adjacent sides of the sections may be flattened and be provided with means substantially throughout the lengths of the 55 sections to secure said flattened sides against

distortion movement in the direction of the length of the series and consequent lengthening of the series as a whole and to localize the expansion to the individual sections. This may conveniently be done by riveting 60 or otherwise securing the adjacent sides of said sections together. To localize or restrict the flexion to the flexion portions of the sections the latter are herein secured together by two vertical rows of rivets wholly 65 within the sections and respectively adjacent the fire-box and the interior sides of the wall. To cover the open sides of said sections a cover sheet 10 preferably common to a plurality of said sections may be riveted or 70 otherwise secured to inturned flanges 13 projecting from the sides of each section.

It is well known that pressure in a container tends to cause the walls thereof to assume a shape of circular cross-section. By 75 my invention the side of each section facing the interior of the fire-box (the side which is subjected to the highest heat) may be convexed or curved to have the shape which the pressure of the steam in the section would 80 tend to cause said side to assume. As a result, the pressure of the steam does not tend to distort said side but, on the contrary, tends to maintain it in its original shape.

Where the adjoining sides of contiguous 85 sections are riveted together substantially throughout their lengths as described or otherwise secured against extension in the direction of the length of the series the pressure tending to distort the sides of the sections is rendered ineffective. Herein this is 90 accomplished by the pressure of the sides of the next adjoining section and as a result tends to maintain the flattened contiguous sides in intimate contact. The adjoining 95 sides are not self-sustaining as are the convexed sides referred to, but rely for support on their supporting means, herein constituting, also, the means for securing one to another thereby to obtain the counteracting 100 effect of one on another for mutual non-extensive support and structural stability.

While I have shown herein each unitary section as comprising integral or seamless construction, it will be understood that my 105 invention includes any unitary section which is complete in itself.

The flexion-sided unitary sections described are each transversely responsive to heat, that is, in the direction of the thick- 110

ness of the wall and may individually assume a change of shape without extension or deformation of the wall as a whole. The adjoining sides of the sections secured together constitute staying members for the outer flexion sides of the wall presenting a construction which is free from objectionable joints and liability of leakage and of great strength throughout. Extension of the sections in the direction of the length of the series is further prevented by the cover sheet 10 common to said sections and securely connected thereto.

Walls such as described above present a simple construction of great strength, having no rivets exposed to the fire. By the curved or bulged sides of the sections the walls are rendered flexible and expansible throughout and particularly on their sides facing the interior of the fire-box where the greatest stress occurs from the temperature variations within the fire-box.

To permit a free circulation through the walls the sections may be connected in any suitable manner as by nipples 15 which may be expanded into the sides of the sections making a tight joint around said nipples. Herein two nipples adjacent the lower ends of the sections are shown, but it will be understood that the nipples may extend as high as desired.

To provide mud-chambers at the bases of the walls through which water may circulate from the barrel of the boiler referred to, the cover plate or sheet 10 of each wall may be extended below the wall as at 16 (Fig. 7) and be riveted or otherwise secured to one side of a mud-ring 17, herein of channel shape, the legs 18 of the channel extending downwardly away from the wall sections to isolate its rivets from the interiors of the latter. Said ring extends the length of the wall and has its opposite side secured to the sections by a suitable connecting strip 19 extending the length of the wall, said sections being suitably flattened as at 20 to receive said strip without leakage between the adjoining sections. To effect a communication between the wall sections at their bases without alteration or weakening of the sections the web of the channel mud-ring may be bent or formed to present a gutter or groove 21 beneath said sections to permit a free flow of water along its length, the gravitation toward the center of the gutter preventing the accumulation of sediment on the top surface of the mud-ring at the sides of the mud-chamber. The mud-chambers may be enlarged, if desired, by removing portions of the lower ends of the sides of the adjoining sections to leave openings 22 above said gutter. These mud-chambers are preferably inclined from the rear to the front of the fire-box (Figs. 1 and 6) to permit any sediment, scale or other accumulation to gravi-

tate to the front of the fire-box and there be flushed out. This inclination may also conform to the inclination of the grate (not shown) and at the same time give proper clearance to the locomotive driving or trail- 70

ing wheels.

Having described the side walls I will now describe the rear or fire-door end wall. This wall (Figs. 1 and 5) herein comprises spaced sheets 24 and 25 which may be stayed in any 75

suitable manner as by usual stay bolts 27. The ends of this wall may be joined to adjacent ends of the side walls by riveting the inner sheet to the end face of the adjoining side wall sections 29. The space between the 80

sheets at the ends of the rear wall may be closed by long flanges 31 on the inner sheet 24 said flanges being bent substantially at right angles to the plane of the inner sheet and extended away from the interior of the 85 fire-box to overlap shorter flanges 33 on and similarly directed from the outer sheet 25.

The side wall cover sheets 10 referred to may be extended beyond the end sections of the side walls as at 34 and be riveted or 90 otherwise secured to one or both of said flanges as desired. Herein said sheets extend substantially to the ends of said flanges and the same rivets 35 serve to unite the flanges together and to said sheets. The end 95

wall may be closed at its lower end by a suitable channel or other shaped mud-ring 37 (Fig. 2). The side and end walls communicate through nipples 39 in the end side 100 wall sections 29 and the adjoining end sheet 24. The top of the end wall is closed in a manner similar to that described for the ends of said wall by a long flange 41 (Figs. 1 and 2) herein constituting a continuation of the long flanges 31 at the ends of the wall, 105

said flange 41 curving gradually from the side walls and extending across the space at the upper end of the front wall to overlap a similarly directed shorter flange 43 projecting from the outer sheet 25. These 110

flanges not only cover the space between the tops of the walls but also constitute bearing supports for a plurality of drums 44 comprising the crown of the fire-box. To this end said flanges are curved or shaped to conform to a portion of the contour of the under faces of said drums. The flanges can be more readily curved or shaped without completely filling the spaces between the drums, the small remaining spaces being readily 120

closed in any suitable manner as by spaced outer and inner cast iron triangular plates 47 (the outer plates only being shown herein) secured together by bolts 49. The spaces between said plates may be filled with asbestos or other non-combustible filling. The water or steam in the end wall may rise into the drums through suitable openings or nipples 51, the latter being entered through and expanded into said long flanges and drums. 130

115

125

130

The drums are provided with suitable heads 45 having man-holes 52 which may be closed by the usual cap-plates 53. The fire-door opening 54 (Figs. 1 and 2) is formed in said 5 end wall by extending a long flange 57 from the inner sheet 24 to and overlapping a similarly directed short flange 59 on said outer sheet 25, said flanges being formed to give the shape of opening desired.

10 The opposite or front ends of the overhead drums referred to are secured to a tube sheet 61 (Figs. 4 and 9) at the front of the fire-box, the central top drum being entered through an opening in said sheet and is 15 riveted or otherwise secured to a flange 63 projecting from said sheet away from the interior of the fire-box. The side drums have at their ends inturned flanges 64 which are riveted or otherwise secured to the fire- 20 side of said tube sheet 61. By this construction the drums are effectively secured and supported and there are no rivets exposed to the fire. Furthermore, any one of the 25 drums may be readily removed for replacement or repair without disturbing the others.

The tube sheet 61 (Figs. 4 and 9) is flanged at its top and sides and is formed to conform to the front outline of the fire- 30 box as determined by the upper portion of the barrel 3 and the fire-box side walls 5 (Fig. 3). The upper portion of the tube sheet flange 65 is riveted or otherwise secured to the adjacent portion of said barrel 35 66 and the side portions of said flange are riveted to portions of a throat sheet 67 which are formed and bent to overlap said flange 65. This throat sheet is also riveted to the under side 68 of the barrel 3, which is 40 cut away as at 69 to provide for the spread of the barrel throat 70 beneath the boiler directly in front of the fire-box. The bottom of the throat may be closed by a suitable mud-ring 71 which is riveted to said tube sheet and throat sheet as shown in Fig. 4. The front sections (Fig. 3) adjoining the tube sheet may be riveted or otherwise secured thereto. Water may be introduced from the barrel 3 through said throat 50 into the mud-chambers of the side walls 5 through suitable openings or nipples 15^a which may be expanded into the sides of said front sections and said tube sheet.

The side walls may be inclined or curved 55 somewhat toward each other to bring the tops of their sections into positions to abut against the sides of the outer drums, said tops being secured to the latter by closing cups 73 which may be riveted, welded or 60 otherwise secured into said sections and to said drums. Water and steam rising in said side walls are permitted to enter said drums through openings or nipples 75 the latter being expanded into said cups and drums.

By my invention are provided side walls 65 each comprising unobstructed sections of great flexibility and strength, having no stay bolts whatever and no rivets exposed to the fire. The side wall mud-chambers do not weaken the walls but, on the contrary, by 70 extending the length of the walls and uniting the sections together contribute substantially to their strength.

The long flange of the inner sheet of the front wall overlapping the short flange of the outer sheet serves both to close the top of the wall and to effectively unite the overhead drums thereto with very few joints and rivets.

It will be obvious that the fire-box described above presents a construction which is extremely simple yet is strong and durable throughout.

It will be understood that my invention is not limited to the particular embodiment shown herein, but that various modifications may be made without departing from the spirit and scope of my invention.

Claims.

1. In a boiler the combination of a series 90 of upright, unitary flexion sections, each having an open side; a chamber at their upper ends with which said sections communicate and are connected; cover means secured to said sections and closing their open 95 sides; and securing means for holding adjacent sides of said sections against distortion movement in the direction of the length of the series thereby to localize the expansion to individual sections. 100

2. In a boiler the combination of a series 105 of upright, unitary wall sections, each having an open side, said sections being respectively self-sustaining and individually expansible transversely of said series; cover means common to the sections for closing their open sides; and securing means for holding adjacent sides of said sections against distortion movement in the direction 110 of the length of the series thereby to localize the expansion to individual sections.

3. In an apparatus of the class described, the combination of a series of upright, unitary wall sections, each having an open side; and cover sheet means secured to said 115 sections and closing their open sides, said sections being respectively self-sustaining and individually expansible transversely of said series.

4. In an apparatus of the class described, 120 the combination of a series of upright, unitary flexion sections, each having an open side; means to secure adjacent sides of said sections together; and cover means secured to said sections and closing their open sides. 125

5. A fire-box comprising, in combination, a series of upright, unitary flexion sections, each having an open side; means to effect

communication through the adjacent sides of said sections; and a cover sheet secured to said sections and closing their open sides.

6. A fire-box comprising, in combination, a series of upright, unitary flexion sections, each having an open side; a cover sheet secured to said sections and closing their open sides; and nipples in the adjacent sides of said sections for effecting communication from one to another.

7. A fire-box comprising, in combination, a series of upright, unitary flexion sections, each having an open side; inturned flanges and a cover sheet secured to said flanges and closing the open sides of said sections.

8. A fire-box comprising, in combination, a series of upright, unitary flexion sections, each having an open side; a cover sheet secured to said sections and closing their open sides; and closing means for the lower ends of said sections.

9. In a fire-box the combination of a wall comprising a series of upright sections; a cover sheet and a plate secured to said sections and projecting beyond opposite sides of the lower ends thereof; and a mud-ring secured to said sheet and plate.

10. In a fire-box the combination of a wall comprising a series of upright hollow sections; and a mud-ring extending across and secured to the lower ends of said sections and having a central gutter extending longitudinally thereof to provide a chamber common to the ends of said sections for delivering water from one to another.

11. In a fire-box the combination of a wall comprising a series of upright sections; a channel mud-ring extending longitudinally of said series and having its back bent to form a gutter to provide a mud chamber beneath the lower ends of said sections.

12. In a fire-box the combination of a wall comprising a series of upright sections; a cover sheet and a plate common to said sections and projecting beyond the lower ends thereof, a mud-ring extending longitudinally of said series and secured to said sheet and plate, said sections communicating with one another directly above said mud-ring to form a mud chamber.

13. In a fire-box the combination of a series of upright, unitary sections each having a convexed flexion side and an open side; a cover sheet secured to said sections and closing their open sides; and securing means for holding adjacent sides of said sections against movement in the direction of the length of the series.

14. A fire-box comprising, in combination, a series of upright, unitary sections, each having a convexed flexion side, an open side and flattened sides; and a cover sheet secured to said open sides and closing the same.

15. A fire-box comprising, in combination,

a series of upright unitary flexion sections, each having an open side; a cover sheet secured to said sections and closing their open sides; and crown drums secured to said sections and communicating therewith.

16. A fire-box comprising, in combination, a series of upright, unitary flexion sections, each having an open side; a cover sheet secured to said sections and closing their open sides; crown drums, and cups secured in the upper ends of said sections and to said drums.

17. A fire-box comprising, in combination, a series of upright, unitary flexion sections, each having an open side; a cover sheet secured to said sections and closing their open sides; crown drums; cups secured to the upper ends of said sections and nipples in said cups and drums for effecting communication from said sections to said drums.

18. In a fire-box the combination of walls each comprising a series of upright, unitary flexion sections, each of the latter having an open side; a cover sheet secured to said sections and closing their open sides; a plurality of adjoining drums constituting the crown of the fire-box; and means providing communication from said walls to said drums.

19. In a fire-box the combination of a plurality of crown drums; and an upright end wall comprising spaced sheets having flanges at their upper ends shaped to conform to the contours of said drums, one of said flanges being extended to overlap the other and bearing against said drums; and means to secure said flanges together and to said drums.

20. In a fire-box the combination of a plurality of crown drums; and an upright end wall comprising spaced sheets having flanges at their upper ends shaped to conform to the contours of said drums and projecting away from the interior of the fire-box, one of said flanges being in direct contact with said drums and extended to overlap the other; and means to secure said flanges together and to said drums.

21. In a fire-box the combination of a plurality of crown drums and an upright end wall comprising spaced sheets having flanges at their upper ends shaped to conform to the contours of said drums, one of said flanges being extended to overlap the other; means to secure said flanges together and to said drums, said drums and one of said flanges being apertured to permit communication between said wall and drums.

22. In a fire-box the combination of a plurality of crown drums and an upright end wall comprising spaced sheets having flanges at their upper ends shaped to conform to the contours of said drums, one of said flanges being extended to overlap the other and bearing against said drums; means to secure

- said flanges together and to said drums; and nipples connecting one of said flanges with said drums for effecting communication between the latter and said wall.
- 5 23. A boiler and its fire box comprising, in combination, a barrel; front and back tube sheets and tubes connecting said sheets; a fire box of which the back tube sheet constitutes the front wall; side walls for said fire-box each comprising a plurality of upright unitary sections, each of said sections having an open side; a cover sheet secured to said open sides and closing the latter; a crown chamber with which said sections 10 communicate at their upper ends and to which they are secured; and means to close the lower ends of said sections.
- 10 24. In a fire-box a wall comprising a plurality of open sided sections nipped together and a cover sheet common to and secured to a plurality of said sections.
- 15 25. In a fire-box a wall comprising a series of sections having flattened, adjoining sides secured together, and flexion sides facing the interior of the fire-box, and a cover sheet common to said sections.
- 20 26. In a fire-box the combination of a side wall comprising tubular sections and an end wall comprising spaced sheets having overlapped flanges at its top and sides, one of said sheets being secured and nipped to the adjoining section of said side wall.
- 25 27. In a fire-box the combination of side walls comprising open sided sections, a cover sheet closing the openings therein and extending beyond said sections, and an end wall comprising spaced sheets having overlapped flanges secured to said cover sheet.
- 30 28. In a fire-box the combination of a side wall comprising a plurality of sections, an end wall comprising spaced sheets having overlapped flanges and a cover sheet secured to said sections and to said flanges.
- 35 29. In a locomotive fire-box, the combination of side walls comprising sections each closed on three sides and a cover sheet closing the other side, crown drums secured to said walls and a barrel communicating with said drums.

30. In a locomotive fire-box, the combination of side walls comprising sections each closed on three sides and a cover sheet closing the other side, an end wall comprising spaced sheets having overlapped flanges, crown drums secured to said side and end walls and a barrel communicating with said drums. 50
- 35 31. In a locomotive fire-box, the combination of side walls each comprising a plurality of open sided flexion shelled sections and a cover sheet for closing the open sides of the latter, an end wall, a tube sheet, a barrel secured thereto and crown drums communicating with each of said walls and with said barrel. 60
- 40 32. In a fire-box, the combination of a series of upright sections having open sides and a cover sheet common to and secured to and closing said sides, each of said sections having portions relatively inextensible in the direction of the length of said series, and a portion expansible toward the interior of the fire-box. 65
- 45 33. In a fire-box, the combination of a series of upright sections individually expansible transversely thereof, and a cover sheet closing and secured directly to said sections. 70
- 50 34. In a fire-box, the combination of a series of upright hollow sections having expansible sides facing the interior of the fire-box, and a cover sheet closing and secured to the opposite sides of said sections. 75
- 55 35. In a fire-box, the combination of a wall comprising a series of upright hollow sections having curved expansible sides facing the interior of the fire-box and open sides opposite thereof, and a cover sheet secured to said sections and closing said open sides. 80

In testimony whereof, I have signed my name to this specification, in the presence of two subscribing witnesses.

JAMES M. McCLELLON.
